UNITED STATES PATENT OFFICE.

PAUL V. GILFILLAN, OF WEST PHILADELPHIA, PENNSYLVANIA, ASSIGNOR TO
UNDERWOOD TYPEWRITER COMPANY, OF NEW YORK, N. Y., A CORPORATION
OF DELAWARE.

TYPE-WRITING MACHINE.

1,151,872.

Specification of Letters Patent. Patented Aug. 31, 1915.

Application filed April 1, 1914. Serial No. 828,664.

To all whom it may concern:

Be it known that I, PAUL V. GILFILLAN, a citizen of the United States, residing in West Philadelphia, in the county of Philadelphia and State of Pennsylvania, have invented certain new and useful Improvements in Type-Writing Machines, of which the following is a specification.

This invention relates to attachments for typewriting machines, particularly adapted to facilitate the rapid and accurate placing of bills or other work forms on the platen in position to be written upon.

In making typewritten entries on a series of forms such as telephone bills and the like, where the amount of typewritten matter on each form is small, a comparatively large proportion of the time required in such work is consumed in placing the forms on the machine and positioning them to be written upon.

An object of the present invention is to provide a contrivance for a typewriting machine which will enable the work forms to be quickly and accurately positioned on the platen, thus resulting in a material saving of time where very many bills are to be placed *seriatim* in the machine and each is to receive only a little writing.

The attachment may be in the form of a chute or guide placed in rear of the platen, and extending beneath and around the platen to the printing line, and positioned and spaced from the platen by suitable means, such as rings secured to the platen to hold the guide a sufficient distance from the platen to permit a work member to be slipped between the guide and platen, and thus quickly brought to printing position,

where it may then be held by pressure rolls (which are released from the platen while the work is being introduced).

Other features and advantages will hereinafter appear.

In the accompanying drawings, Figure 1 is a front perspective view of an Underwood platen and frame, with the present invention applied thereto. Fig. 2 is a skeleton perspective view showing the paper-guide or chute, and the rings for positioning said chute relatively to the platen. Fig. 3 is a sectional end elevation view through the

platen and paper-guide. Fig. 4 is a fragmentary sectional front elevation.

A rotary platen 1 is fixed to a platen axle 55 2 journaled in the ends 3 of the platen frame, which may also comprise the usual inclined paper shelf 4, located at the rear of the platen and connecting the platen frame ends. A chute 5, by means of which a bill or other work member is guided to position to be written upon, comprises a body portion 6, which lies over the paper shelf 4 and may be held in position by any suitable means, as bolts 7. The lower portion 60 65 of the chute is curved to conform to the curved surface of the platen, and extends downwardly beneath the platen and up toward the printing line, the front edge 8 forming a gage for the printing line. 70

The chute 5 is spaced from the platen to provide a narrow passageway 9 through which the work members slip as they are placed on the chute and pushed forward to printing position. The chute may be 75 thus positioned by means of rings 10, of metal or other suitable material, secured by pins 11, or otherwise, to the platen. Said rings are formed at their inner edges with flanges 12 on which the lower curved edges 80 13 of the chute are supported to maintain a space or passageway between the chute and platen, said rings also providing shoulders 14 which serve as opposite guides or gages to engage the opposite lateral edges 85 of the work members, to confine them against displacement, and bring them accurately to printing position. Flanges 15 extending along the edges of the flat portion 6 of the chute also serve as side gages for 90 the work members.

When a work member has been placed on the chute 5 and slipped forward to printing position and adjusted to the platen scale 8, it may be clamped by feed rolls 16, mounted 95 upon a swinging rod 17 carried by rock arms 18 journaled on a rod 19 extending between the ends of the platen frame. The feed rolls are yieldingly held against the platen by springs 20, and may be lifted from 100 the platen by means of rock arms 21 secured to the arms 18 and actuated by cam faces 22, on a rock shaft 23, actuated by a finger lever 24 connected through a link

25 to an arm 26 on the shaft 23. The lever 24 is depressed prior to the insertion of a work member, to lift the feed rolls from the platen, the rolls remaining in such position when pressure on the lever 24 is removed, and after the work is in position, said lever is returned to restore the pressure rolls and thus clamp the work in position. The work may be additionally held 10 by a Y-shaped spring clamp 27, secured to the rod 17 and extending within a notch or opening in the scale 8, and movable toward and from the platen together with the feed rolls. This form of clamp is in common use on the Underwood typewriting machine.

The chute 5 is cut away at 28 to provide space to accommodate the feed rolls, and the edges 29 above said spaces 28 are preferably 20 beveled or turned outward, as shown, to prevent the edge of the work sheet from catching thereon.

It will be seen that the present invention provides a means for quickly and accurately 25 positioning the bill, or other work form, on the platen, and permits quick removal after it has been written upon. This is of special value in making entries upon a series 30 of work forms of uniform size, such as telephone bills, and the like, where the amount of writing on each bill is comparatively small, and the rapid insertion and removal of the work members results in a material saving of time when a long list of such bills 35 is handled. The chute 13 is entirely clear of the platen, so that a sheet may be freely slipped around the platen to printing position when the feed rolls are cast off.

Variations may be resorted to within the 40 scope of the invention, and portions of the improvements may be used without others.

Having thus described my invention, I claim:

1. The combination with a rotary platen, 45 of a paper guide or chute curved to conform to the periphery of the platen, and means on the platen for spacing said chute therefrom to permit a work member to be slipped into position between said chute and the platen.

2. The combination with a rotary platen, 50 of a paper guide or chute curved to conform to the periphery of the platen, and rings secured to the platen in position to space said chute from the platen.

3. The combination with a rotary platen, 55 of a paper guide having a portion curved to conform to the periphery of the platen, and rings secured to the platen and provided with flanges between the platen and the edges of the said guide to space the guide from the platen.

4. The combination with a rotary platen, 60 of a paper guide comprising an inclined shelf having flanges along its lateral edges

to gage a work member, and a curved portion to extend around and beneath the platen, and rings secured to the platen and extending between said curved portion and the platen to space said guide from the 70 platen.

5. The combination with a rotary platen, 75 of a stationary work-sheet guide mounted at the introductory side of the platen and extending forwardly around the platen about to the printing line, and spaced from the platen to permit the work-sheet to be slid between the platen and said guide to position to be written upon, and lateral guiding means for the work-sheet at each side of 80 said stationary guide to guide the sheet both at the introductory side of the platen, and near the printing line.

6. The combination with a rotary platen, 85 of a stationary work-sheet guide mounted at the introductory side of the platen and extending forwardly around the platen about to the printing line, and spaced from the platen to permit the work-sheet to be slid between the platen and said guide to position 90 to be written upon, lateral guiding means for the work-sheet at each side of said stationary guide to guide the sheet both at the introductory side of the platen, and near the printing line, and reasonable means 95 movable independently of said stationary guide to hold the work-sheet against the platen.

7. The combination with a rotary platen, 100 of a stationary work-sheet guide mounted at the introductory side of the platen and extending forwardly around the platen about to the printing line, and spaced from the platen to permit the work-sheet to be slid between the platen and said guide to 105 position to be written upon, lateral guiding means for the work-sheet at each side of said stationary guide to guide the sheet both at the introductory side of the platen, and near the printing line, and releasable 110 means movable independently of said stationary guide to hold the work-sheet against the platen, and including a pair of rolls passing through openings in said stationary guide near the forward edge thereof.

8. The combination with a rotary platen, 115 of a stationary work-sheet guide mounted at the introductory side of the platen and extending forwardly around the platen about to the printing line, and spaced from the platen to permit the work-sheet to be slid between the platen and said guide to position 120 to be written upon, lateral guiding means for the work-sheet at each side of said stationary guide to guide the sheet both at the introductory side of the platen, and near the printing line, and releasable means 125 movable independently of said stationary guide to hold the work-sheet against the platen, and including a pair of rolls passing 130 through openings in said stationary guide.

ing through openings in said stationary guide near the forward edge thereof, and also including a yielding finger to press the work-sheet against the platen approximately 5 at the printing line.

9. The combination with a rotary platen, of a paper guide or chute curved to conform to the periphery of the platen, and comprising a portion extending upwardly from the 10 introductory side of the platen, said portion having side gages at its opposite edges, and means between the platen and the curved portion of said chute arranged in line with said gages, to gage the forward portion of 15 the work-sheet.

10. The combination with a rotary platen, of a paper guide or chute curved to conform to the periphery of the platen, and comprising a portion extending upwardly from the 20 introductory side of the platen, said portion having side gages at its opposite edges, and means between the platen and the curved portion of said chute arranged in line with said gages, to gage the forward portion of 25 the work-sheet, said forward gaging means being disposed between the platen and the chute, to separate the chute from the platen.

11. The combination with a rotary platen, of a paper guide or chute comprising a portion extending upwardly from the introduc- 30

tory side of the platen and a portion curving forwardly around the platen, opposite side gages provided upon said chute in rear of the platen, and rings secured to the platen in line with said side gages, both to gage the 35 forward side portions of the sheet and also to space the chute from the platen.

12. The combination with a rotary platen, of a stationary work-sheet guide mounted at the introductory side of the platen and having an extension running forwardly around the platen and up about to the printing line, and spaced from the platen to permit the sliding of the work-sheet forwardly between the platen and guide to position to be written upon, guiding means for both side edges of the work-sheet arranged at the sides of said stationary guide, for controlling the sheet both at the introductory side of the platen and near the printing line, yielding 50 means seated in a recess located at the forward end of said extension to press the work-sheet against the platen approximately at the printing line, and means to release said yielding means from the platen.
